UNITED STATES PATENT OFFICE.

CHARLES D. SMITH, OF WASHINGTON, DISTRICT OF COLUMBIA, ASSIGNOR
TO HIMSELF AND JOHN A. WIEDERSHEIM, OF PHILADELPHIA, PA.

COMBINED ERASER AND PENCIL-SHARPENER.

Specification forming part of Letters Patent No. 58,558, dated October 2, 1866.

To all whom it may concern:

Be it known that I, CHARLES D. SMITH, of the city and county of Washington, in the District of Columbia, have invented a new and useful Combined Eraser and Pencil-Sharpener; and I do hereby declare the following to be a full, clear, and exact description of the nature, construction, and operation of the same, reference being had to the accompanying drawing, which is made a part of this specification, and which represents a perspective view, partly in section, of my improved device.

The object of this invention is to combine as one the two instruments which have hitherto been employed separately, for the respective functions of erasing ink and sharpening pencils; and by this language my invention may be readily distinguished from erasers in which the blade or cutter is constructed with a file-groove or a cutting-edge, especially designed for sharpening pencils. The pencil-sharpener, which constitutes an element of the present combination, consists of a conical metallic cutter—that is to say, a device having a conical interior essentially, and an internal knife, straight, spiral, or of any other suitable form, and adapted by rotation to give the desired taper or conical form to the end of the pencil when introduced.

I construct an eraser by securing the erasing knife or cutter A in one end of the handle B in any suitable manner. In the other end of this handle I insert, and secure in any desira-

ble way, a pencil-sharpener, C, which may be constructed in any manner, so long as it is adapted to receive the end of the pencil and by rotation cut the same, so as to give it the required taper or conical form. The pencil-sharpener, thus inserted, may have its edge or mouth flush with the end of the eraser, if preferred, and, under any mode of application, the end of the eraser may be strengthened by a metallic band or otherwise.

The combination may be effected in other ways, substantially the same as the method above described—as, for instance, the pencil-sharpener may be constructed with a threaded collar adapted to be screwed onto the end of the handle B, and thus permit the pencil-sharpener to project beyond the said handle. In the former case—that is to say, when the pencil-sharpener is inserted in the end of the handle B—the latter is slotted, as at e, so as to allow the chippings from the pencil to find ready egress from the interior of the pencil-sharpener while the latter is in operation.

Having thus described my invention, what I claim as new, and desire to secure by Letters Patent, is—

The combination, with an eraser, of a pencil-sharpener having substantially the characteristics herein specified.

CHARLES D. SMITH.
